SAMUEL G. CRANE, OF TOLEDO, OHIO, ASSIGNOR TO TOLEDO SCALE COMPANY, OF TOLEDO, OHIO, A CORPORATION OF NEW JERSEY.

ELECTRICAL CONNECTOR.

1,248,272.

Specification of Letters Patent. Patented Nov. 27, 1917.

Application filed January 27, 1915. Serial No. 4,798.

To all whom it may concern:

Be it known that I, SAMUEL G. CRANE, a citizen of the United States, residing at Toledo, in the county of Lucas and State of Ohio, have invented certain new and useful Improvements in Electrical Connectors, of which the following is a specification.

This invention relates to connectors and conductor systems for transmitting electricity, and has for its primary object to provide a simple and efficient connector and conductor system wherein provision is made for utilizing electrical currents of different strengths, so as to enable the connector and the conductors connected therewith to be used under many varying conditions.

A further object of the invention is to provide a simple and inexpensive connector and conductor system with a novel arrangement of multiple contacts and wiring connections whereby currents of greatly varying strengths may be transmitted therethrough, while providing means for automatically distinguishing between the proper and incorrect contacts for a current of known strength, enabling the connector to be used as a safeguard against improper connections whereby the conductors leading therefrom might be injured or destroyed through carelessness, ignorance, or mistake.

More particularly, the connector and conductor system herein disclosed is designed to provide a connecting and conducting means that will allow currents of different strengths, as for example, of 110 and 220 volts, to be utilized to illuminate the same set of electric lamps, the wiring system whereby the current is transmitted through the lamps being automatically changed by suitable arrangements of the contact devices carried by the connector.

Reference is to be had to the accompanying drawings, illustrating a preferred embodiment of my invention and wherein similar reference numerals designate similar parts throughout the several views.

In the drawings, Figure 1 is a view in front elevation with parts in section of my improved connector arranged to illuminate the same set of lamps with currents of two different strengths, with a portable connector in position to transmit the current of greater strength.

Fig. 2 is a plan view of the connector with a diagrammatic view of the lamps and the

wiring connections, the wiring systems utilized to transmit the current of greater strength, being shown in full lines, and the auxiliary wiring connections not used in the transmission of the current of greater strength being shown in dotted lines.

Fig. 3 is a sectional view of the connector with a diagrammatic view of the lamps and wiring system utilized to transmit the current of less strength, the auxiliary wiring connections not used in the transmission of the current of less strength being shown in dotted lines.

In the drawings, 5 designates a portable connector of the ordinary type adapted to be inserted into a suitable fixed socket and carrying at its free end a pair of sprung tined prongs 6. The numeral 7 designates a connector plug formed as herein shown of a block or disk of insulating material 75 having three aligned openings therein, two of said openings 8 being relatively deep and the remaining opening 8^a relatively shallow, as clearly shown in Figs. 1 and 3.

In the shallow opening 8^a is arranged a contact ring 9 having suitable connections with a binding post 9^a at the periphery of the connector plug. Within each of the deep openings are arranged two contact rings 10, one of said rings being secured adjacent the upper extremity of each opening and the other of said contact rings being secured adjacent the lower extremity thereof. One of deep openings 8—i. e. that arranged nearest the periphery of the connector plug—has suitable connections between the upper of its contact rings 10 and the binding post 13, while the lower of its contact rings is suitably connected to a binding post 13^a substantially as arranged in Fig. 1. The other of said deep openings 8, hereinafter referred to as the central opening, is arranged between the shallow opening 9 and the first-mentioned deep opening 8 of the connector plug. The upper and lower contact rings 10 in this central opening are connected by wires 11 and 11^a respectively, extending from said contact rings to binding posts 12 and 12^a located at diametrically opposite points on the periphery 105 of the connector or plug (see Fig. 2).

When it is desired to utilize a current of say 220 volts, the sprung tined prongs 6 of the portable connector are arranged as shown in Fig. 1 of the drawings, with one

of said prongs extending into the shallow opening 9 and the other prong in contact with the upper of the contact rings 10 of the central opening 8. When so connected 5 the wiring connection from the binding post 90 attached to the contact ring of the shallow opening 9 extends to a lamp 14 shown at one extremity of the row of lamps in Fig. 1 by a wire leading through the upper portion 10 of the lamp marked 15, thence to the third lamp of said row, marked 16, from which lamp a return connection is made to the upper contact ring of the central opening 8. The second and fourth lamps of 15 the row, marked 15 and 17 respectively in the drawings, are wired in the same manner, the connection leading from the binding post 9^a to the lamp marked 15, thence to the lamp marked 17, from which lamp the return 20 is made to the upper contact ring of the central opening 8 through the wire leading through the upper portion of lamp marked 16 and the return wire from this lamp. This wiring system forms substantially a multiple series system wherein 25 lamps 14 and 16 are so connected that the extinguishment of one by break of the circuit therein would result in the extinguishment of the other, though not affecting the lighting of the other lamps of the row—to wit, lamps marked 15 and 17. The same connection allows the simultaneous extinguishment of the lamps 15 and 17 of the row without affecting the illumination of 30 lamps 14 and 16 of the row.

When, however, it is desired to utilize a current of 110 volts for lighting the same lamps 14, 15, 16, and 17, the prongs of a suitable portable plug are inserted into the 35 two deep apertures 8 into contact with both the upper and lower contact rings therein. When so connected each lamp in the row has substantially an individual circuit, the wiring system being arranged so that the 40 lamps are wired in multiple. To illuminate the lamp marked 14, connection is made from the binding post 13^a attached to the lower contact ring of the aperture 8 adjacent the periphery of the disk 7 to lamp 45 14 and the return is made directly from said lamp to the binding post 12 attached to the lower contact ring of the central aperture 8 (see Fig. 3). To illuminate the lamp marked 15, connection is made from the 50 binding post 13 attached to the upper contact ring of the aperture 8 adjacent the periphery of the disk to lamp 15, thence the return is made to the binding post 12 attached to the lower contact ring of the central aperture. To illuminate the lamp 55 marked 16 connection is made from the binding post 13^a attached to the lower contact ring of the aperture 8 adjacent the periphery of the disk to the lamp 16 and the 60 return is made to the binding post 12^a at-

tached to the upper contact ring of the central aperture. To illuminate the lamp marked 17, connection is made from the binding post 13 attached to the upper contact ring of the aperture 8 adjacent the periphery of the disk to the lamp 17, and the return is made to the binding post 12^a attached to the upper contact ring of the central aperture. This wiring system forms substantially a multiple system wherein each 70 of the lamps 14, 15, 16 and 17 are provided with an individual circuit and the extinguishment of one will not affect the illumination of the others.

It will be apparent from the above that 80 this connector provides a system of contacts arranged so that when a current of 110 volts is utilized the lamps will be individually supplied, while in order to utilize a current of 220 volts a second series of contacts are 85 provided wherein alternate lamps of the row are connected in series and these series connections arranged in multiple enabling the stronger current to be used without injuring or destroying the lamps. 90

Further the simplicity of the arrangement insures the correct usage of the connector by all who may have occasion to utilize the same, and the adaptation of the same connector and the same set of lamps, etc., to a 95 plurality of currents of varied strengths renders the connector capable of usage under many and varied working conditions.

It is to be understood that the connector herein shown may be used in the transmission of current for other purposes than the illumination of a row of lamps, and the connection herein disclosed is not to be limited to the illustrative embodiment herein shown, but many modifications or additions may be 100 made thereto without departing from the spirit and scope of my invention, as set forth in the following claims.

Having described my invention, I claim:—

1. An electrical connector and conductor 110 system comprising a block of insulating material having two relatively deep openings and one shallow opening therein, a single contact device arranged in the shallow opening and a pair of spaced contact devices arranged in the two deep openings, wiring connections between the contact device in the shallow opening and one of the contact devices in one of said deep openings, and wiring 115 connections between the several contacts of said deep openings.

2. An electrical connector and conductor system comprising a block of insulating material having two relatively deep openings and one shallow opening therein, a single contact device arranged in the shallow opening and a pair of spaced contact devices arranged in the two deep openings, wiring connections between the several contact devices in said deep openings, and wiring 125 con- 130

nections between the contact device in said shallow opening and one of the contact devices in one of said deep openings.

3. An electrical connector and conductor system comprising a block of insulating material having two relatively deep openings and one shallow opening therein, a single contact device arranged in the shallow opening and a pair of spaced contact devices arranged in the two deep openings, wiring connections from the several contacts in the

two deep openings for transmitting current through multiple circuits, and wiring connections from the contact device of said shallow opening and one of the contacts of 15 said deep openings for transmitting current through multiple series circuits.
